UNITED STATES PATENT OFFICE.

JOHN PORTER SHEARER, OF NYACK, NEW YORK, ASSIGNOR TO HEYWOOD, STRASSER & VOIGT LITHOGRAPHIC COMPANY, OF NEW YORK, N. Y., A CORPORATION OF NEW YORK.

COMBINED SHOW-CARD AND DISPLAY-RACK.

1,182,936.

Specification of Letters Patent.

Patented May 16, 1916.

Application filed May 15, 1915. Serial No. 28,295.

To all whom it may concern:

Be it known that I, JOHN PORTER SHEARER, a citizen of the United States, and a resident of the village of Nyack, in the county of 5 Rockland, State of New York, have invented certain new and useful Improvements in Combined Show-Cards and Display-Racks, of which the following is a specification.

The invention relates to devices for displaying and advertising goods for sale, and its objects are, among others, to provide a device of this character which may be made of card board or other similar material, and is so constructed and arranged that when 10 not in use its parts may be folded one upon another so that they will occupy the space of but a few sheets of the material so as to be convenient for packing, shipping and storing, and which when placed in position for use 15 will be self-supporting in an upright position, will afford a suitable surface for the display of advertising or other printed matter and will also support samples of the goods in connection with which they are 20 used.

Further objects are the construction and arrangement of the parts so as to reduce the cost of manufacture and obtain a maximum of efficiency for the purpose designed.

The invention consists in the construction and arrangement of parts hereinafter described and claimed and illustrated in the drawings.

In the said drawings, Figure 1 is a front 35 elevation of a combined show card and display rack embodying the improvements. Fig. 2 is a side elevation of the same. Fig. 3 is a plan of the two parts of which the device is composed before assembling. Fig. 4 40 is a side view of the support.

The board A is composed of a sheet of card board or other material, upon the face of which may be printed or otherwise displayed any desired reading matter or design. It is provided with apertures B and C made by punching out the material. As 45 many of these apertures as is desired may be provided, or only one may be used. From the lower corners of the apertures slits D 50 extend downwardly, so that the material may be turned outwardly to form a shelf E. The material is also provided centrally with a slot F adapted to receive the hook of the supporting bracket, and a short distance be-

low each opening is an open-ended slot N 55 which receives the said bracket.

The parts above described are made of one piece of sheet material, and, as will be seen, may be formed by one movement of a suitable die.

The member G consists of a substantially triangular piece of sheet material, secured to the back of the board, and forming a support therefor, so that the entire device presents an appearance similar to that of 65 an easel. It has angular cut-out portions H and I corresponding in length to the openings B and C, and, when the parts are assembled positioned behind said openings. Extensions J and K proceed from the bottom of these cut-out portions, and the material, at the point where these extensions join the bottom of the support G, is provided with slots L and M. The upper end or apex of the support G is also provided 70 with an extension P, which may be folded sidewise and pasted or otherwise secured to the back of the board A to secure the parts together. The extremities of the extensions J and K have an upward and slightly in- 75 ward projection forming a catch or hook O which passes through the slot F of the shelf and holds the said shelf in position. The resiliency of the material will be sufficient to permit this catch to operate, without other 80 provision.

The engagement of the two members of the device below the openings is provided for by the slots L and M which permit the extensions J and K, after passing through 90 the slots N, to move upwardly and engage on opposite sides of the board A. In this manner the parts of the device, when the portion P is secured to the back of the board, are securely held against separation.

After the device is assembled the extensions J and K forming the supporting brackets, the shelves E supported thereby and the portion of the support G at the back of the board may all be turned so as to lie flat 100 against the front and back of the board, until they are put in use. It will be seen that the shelves, and the lower edges of the cut-out portions of G form a horizontally disposed support for an article placed therein, and that the rear edge of said cut-out portions and the sides of the openings of the board form vertically disposed supports 105

which prevent said article from moving horizontally. It will be understood that these openings may be of any desired form and size, to accommodate the article intended to be supported therein.

In the device as shown the folding over of the parts may be provided for by taking a sheet of card board, or other material, and scoring it at one side of the line of the fold, then turning the material back so that the scored portion acts as a hinge.

One or more of the openings B may be employed, as desired, the upper end of the support G may be secured to the board A in any other desired manner, as, for instance, in manner similar to the securement of the lower edge, and the shelves E and other parts may be non-integral with the board or omitted entirely. Other changes in the details of construction and arrangement may also be made without departing from the spirit and scope of the invention. It will also be understood that in making the device of metal or other rigid material some of the parts will be modified within the scope of the invention. Thus the shelf E will be punched out and severed from the sheet and at the same time provided with notches in its side edges by which it may be positioned and held in the bottom of the opening.

What I claim is:

1. A device of the character described, comprising in its construction a piece of sheet material provided with an opening therein, a shelf at the lower part of said opening, said sheet having cuts extending below the normal opening, and the said shelf being formed by turning down the material between the cuts; said shelf also provided with a slot at its outer part, a brace or support for holding the said sheet in an upright position and supporting objects placed in said opening, consisting of a piece of sheet material having an angular cut-out portion opposite the opening, an extension at the bottom of said cut-out portion passed through the said sheet, a slot in the sheet through which the same may be passed and a slot in the extension to receive a portion of the sheet, and an upwardly projecting portion passing through the slot of the shelf and extending over the material at the end of said slot, whereby the said shelf is supported vertically and the extension supported against lateral movement.

2. A device of the character described, comprising in its construction a piece of sheet material provided with an opening therein, a shelf at the lower part of said opening, said sheet having cuts extending below the normal opening, and the said shelf being formed by turning down the material between the cuts, said shelf also provided with a slot at its outer part, a

brace or support for holding the said sheet in an upright position and supporting objects placed in said opening, consisting of a piece of sheet material having an angular cut-out portion opposite the opening, an extension at the bottom of said cut-out portion passed through the said sheet, a slot in the sheet through which the same may be passed and a slot in the extension to receive a portion of the sheet, and an upwardly projecting portion passing through the slot of the shelf and extending over the material at the end of said slot, whereby the said shelf is supported vertically and the extension supported against lateral movement, and a portion of the said supporting member turned at substantially right angles thereto and secured to the back of the sheet.

3. A device of the character described, comprising in its construction a piece of sheet material provided with an opening therein, a shelf at the lower part of said opening formed by a displaced portion of the sheet, said sheet having cuts extending below the normal opening, a brace or support for holding the said sheet in an upright position and supporting objects placed in said opening, consisting of a piece of sheet material having cut-out portion opposite the opening, an extension below said cut-out portion passed through the said sheet, whereby the said shelf is supported vertically, the said parts being constructed and arranged so that all may be turned to lie in parallel planes with the supporting member and its extension in contact with the front and back of the sheet respectively.

4. The combination of a sheet of material having an opening therein, and adapted to be placed in an upright position, a shelf extending laterally therefrom adjacent to the opening, a supporting member located on the side of the sheet opposite that from which the shelf extends and having a portion extending therethrough and supporting the said shelf, and also forming a connection between the said supporting member and the sheet.

5. The combination of a sheet of material having an aperture therein and a supporting member arranged on one side of said sheet and adapted to support it in an upright position when turned to a position angular thereto, connections between said supporting member and sheet permitting the former to move to a position substantially parallel therewith and away from said position, said supporting member having a cut out portion opposite the said aperture, and adapted to coöperate therewith for the reception and support of articles placed therein, and also having a portion extending through said sheet to form a support.

6. The combination of a sheet of material having an opening therein, and adapted to

be placed in an upright position, a shelf extending laterally therefrom adjacent to the opening, said shelf formed of material displaced in making the opening and connected 5 with said sheet at one edge, a supporting member located on the side of the sheet opposite that from which the shelf extends and having a portion extending therethrough and supporting the said shelf, and also 10 forming a connection between the said supporting member and the sheet.

7. The combination of a sheet of material having an aperture therein, a shelf extending laterally therefrom, and a supporting 15 member of sheet material arranged on one side of said sheet and adapted to support it in an upright position when turned to a position angular thereto, connections between said supporting member and sheet permitting 20 the former to move to a position substantially parallel therewith and away from said position, said supporting member having a cut-out portion opposite the said aperture and adapted to coöperate therewith for 25 the reception and support of articles placed therein, and also having a portion extending through said sheet to form a support.

8. A device of the character described, comprising a sheet of material, a supporting 20 member of sheet material connected therewith and extending therefrom to support the same in an upright position, said sheet

having an opening therein, and a shelf extending therefrom on the side opposite the supporting member composed of a portion 35 of the material displaced in making the opening, but joined to the sheet at one side of said opening, and said supporting member having a portion extending through the sheet and forming a support for said shelf. 40

9. A device of the character described, comprising a sheet of material, a supporting member of sheet material connected therewith and extending therefrom to support the same in an upright position, said sheet 45 having an opening therein, and a shelf extending therefrom on the side opposite the supporting member composed of a portion of the material displaced in making the opening, and said supporting member having 50 a portion extending through the sheet and forming a support for said shelf, the connection between the said supporting member and the sheet being flexible and permitting the supporting member and its extending portion to be turned to a position 55 substantially parallel with the sheet.

Witness my hand this 11th day of May, 1915, at the city of New York, N. Y.

JOHN PORTER SHEARER.
